UNITED STATES PATENT OFFICE.

HARRY MORRIS, OF CHICAGO, ILLINOIS.

DESIGN FOR A DISPLAY-CABINET.

60,053.

Specification for Design.

Patented Dec. 20, 1921.

Application filed April 9, 1921. Serial No. 460,082. Term of patent 7 years.

To all whom it may concern:

Be it known that I, HARRY MORRIS, a citizen of the United States, residing at Chicago, county of Cook, and State of Illinois, have invented a new, original, and ornamental Design for a Display-Cabinet, of which the following is a specification, reference being had to the accompanying drawing, forming a part hereof, in which—

The drawing shows the display cabinet in perspective.

I claim:

The ornamental design for a display cabinet, as shown.

HARRY MORRIS.
